(73) Assignee: **ADP Distributors, Inc.**, Surrey, B.C.
(CA)

Primary Examiner — Patricia Palasik

(74) *Attorney, Agent, or Firm* — Dwayne E. Rogge; Schacht
Law Office, Inc.

(**) Term: **14 Years**

(57) **CLAIM**

The ornamental design for a hydraulic turbocharger pedestal
seal, as shown and described.

(21) Appl. No.: **29/396,516**

DESCRIPTION

(22) Filed: **Jun. 30, 2011**

FIG. 1 is a side view from all sides of a first embodiment
thereof, as the seal is symmetrical about a long axis.

(51) **LOC (9) Cl. 15-99**

FIG. 2 is a front isometric view thereof.

(52) **U.S. Cl.**

FIG. 3 is a rear isometric view thereof.

USPC **D15/144**

FIG. 4 is a front view thereof.

(58) **Field of Classification Search**

FIG. 5 is a rear view thereof.

USPC D15/144, 144.1, 144.2; 137/516.13-516.27;

FIG. 6 is a cross-sectional view taken along line 6-6 of FIG. 4.
FIG. 7 is a side view from all sides of a second embodiment

251/368; 277/602, 608, 625-626;

thereof, as the seal is symmetrical about a long axis.

285/104-105, 337; D23/269

FIG. 8 is a front isometric view thereof.

See application file for complete search history.

FIG. 9 is a rear isometric view thereof.

(56) **References Cited**

FIG. 10 is a front view thereof.
